UNITED STATES PATENT OFFICE.

LUCIAN S. GROVES, OF BOSTON, MASSACHUSETTS, ASSIGNOR, BY MESNE ASSIGNMENTS, TO STEWART MANUFACTURING COMPANY, OF BOSTON, MASSACHUSETTS, A CORPORATION OF MASSACHUSETTS.

BOTTLE CAP.

Application filed January 16, 1926. Serial No. 81,717.

This invention relates to bottle closures and more particularly to a novel sanitary cap for milk bottles.

The primary object of the present invention is the provision of a molded bottle cap having a novel protecting skirt for receiving the upper end or bead of the milk bottle, so as to effectively prevent the settling of dust, dirt and the like on the pouring lip of the bottle and the entrance of foreign matter into the bottle upon the removal of the cap from the bottle neck.

Another primary object of the invention is the provision of a novel bottle cap, which can be molded from a low grade of material, such as wood pulp and which can be readily stacked one upon the other to permit the use thereof in automatic bottle capping machines.

A further object of the invention is the provision of an improved milk bottle cap embodying an annular protecting dust skirt, the cap being so formed as to provide a triple seal, whereby the entrance of dust, dirt and the like into the bottle and the loss of the cap is absolutely precluded.

A further object of the invention is the provision of novel means for forming the cap, whereby the inside closure seat will tend to be forced tighter in engagement with the interior diameter of the bottle neck when the same becomes moist or wet, the skirt tending to grip the bead of the bottle tighter as the same dries out.

A further object of the invention is the provision of novel means for forming the molded cap in such a manner as to permit the association therewith of the ordinary disk bottle cap having the usual dairy advertisement thereon.

A further object of the invention is the provision of a bottle cap formed of molded material having a concavo-convex depression in its lower face forming an expansion chamber to permit the effective taking care of the expansion of the milk in the bottle after the delivery of the milk.

A further object of the invention is the provision of a novel air chamber formed within the dust skirt upon the association of the cap with the bottle neck to permit different sizes of bottles to be taken care

of and to allow the expansion and contraction of the cap as well as the bottle.

A still further object of the invention is the provision of a novel sanitary bottle cap of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a fragmentary side elevation of a milk bottle neck partly broken away in section with the improved cap associated therewith, the cap being shown in diametric section.

Figure 2 is a top plan view of the improved cap,

Figure 3 is a side elevation of the same,

Figure 4 is a bottom plan view of the improved cap,

Figure 5 is a bottom plan view of the cap showing a slightly modified form thereof, the cap having parts thereof broken away and in section,

Figure 6 is a diametric section through the modified form of the cap taken on the line 6-6 of Figure 5,

Figure 7 is a detail plan view of the expansion ring utilized in the modified form of cap, and

Figure 8 is a detail plan view of the contraction ring used in the modified form of the cap.

Referring to the drawings in detail, wherein similar reference characters designate corresponding parts throughout the several views, the letter A indicates a milk bottle of the ordinary character and B the novel improved milk bottle cap therefor.

As stated the milk bottle A is of the conventional form and includes the usual neck 10 having the pouring bead 11 and the inferior annular seat 12 against which is normally fitted the usual closure disk.

The improved milk bottle cap B is formed from molded material, such as wood pulp owing to the cheapness thereof and if pre-

ferred the cap can be coated or impregnated with paraffin or some other liquid-proof material. However, it is preferred to leave the cap in its original molded condition, in view 5 of certain inherent characteristics of the cap formed from paper pulp when left in its plain state.

The improved cap B comprises a relatively thick disk shaped body portion 15 having 10 formed on the upper edge thereof the annular depending dust protecting skirt 16. This skirt 16 is of an arcuate configuration in cross section and is more or less of a 15 springy nature, so as to snap over the bead 11 of the neck of the milk bottle. If preferred the main body portion 15 can be gradually flared outwardly as at 17 so as to insure snapping of the same in position on the seat 12 formed within the bottle neck. 20 It is to be understood that the body is forced into position within the milk bottle neck and forms a tight seal therewith, which is the first means for sealing the bottle. The skirt 16 is of such a size and configuration as to 25 receive the entire bead 11 and thereby fully cover the same and this skirt forms a dual seal with the bead. Thus the skirt engages the upper outer edge of the bead, as indicated by the reference character 18 and beneath 30 the bead, as indicated by the reference character 19. Thus the entire cap forms a triple seal preventing the ingress or egress of material from or into the bottle. The lower 35 face of the main body portion 15 of the cap is provided with a concaved depression 20 which provides for the expansion of the milk within the container and it is also obvious, that from the formation of this depression that the cap is increased in width at its 40 outer edge to form the flange for fitting upon the seat 12. An air space 21 is also formed between the skirt and the upper edge of the bead 11 and this air chamber prevents creeping of moisture and the like into the bottle 45 and also allows the skirt 16 to conform to different sizes of beads on the milk bottle necks.

The upper face of the body 15 is provided with a disk shaped depression 22 into which is adapted to be brought the ordinary disk shaped milk cap bearing the name of the 50 dairy using the improved cap. The milk bottle disk (not shown) can be sprung into the depression 22, while the cap is in a wet condition.

In use of the improved caps, the same are 55 placed one upon the other and can be successfully used in an automatic bottle capping machine.

Attention is invited to the fact, that if the body portion 15 becomes wet, the same 60 will have a tendency to swell forming a tight fit with the seat 12 of the bottle neck and the skirt 16, which is exposed to the air will tend to dry thus contracting tighter about 65 the bead of the bottle.

In Figures 5 to 8 inclusive I have shown a slightly modified form of the invention, in which an expansion ring 25 of the split type can be molded directly into the body 15 adjacent to the lower outer edge thereof, so as 70 to insure the strengthening of the cap at that point and to normally hold the cap in intimate contact with the seat 12. A contractile split ring 26 is also embedded in the skirt 16 adjacent to its lower edge, so as to 75 strengthen the skirt and to normally hold the skirt in intimate contact with the said bottle neck.

Changes in details may be made without departing from the spirit or scope of this 80 invention, but:

What I claim as new is:

A milk bottle closure comprising a body plug and a skirt formed on the periphery of the plug at the upper edge thereof depending from the body plug and in spaced relation thereto, an expansion ring carried by the body plug adjacent to the lower edge thereof, and a contraction ring embedded in the skirt at the lower end thereof. 90

In testimony whereof I affix my signature.

LUCIAN S. GROVES.
